UNITED STATES PATENT OFFICE

92,845

DESIGN FOR A FAUCET MOUNTING

Robert S. Grogan, Chicago, Ill.

Application May 14, 1934, Serial No. 51,782

Term of patent 14 years

To all whom it may concern:

Be it known that I, ROBERT S. GROGAN, a citizen of the United States, residing at Chicago, county of Cook, and State of Illinois, have invented a new, original and ornamental Design for a Faucet Mounting, of which the following is a specification, reference being had to the accompanying drawing forming a part thereof.

Fig. 1 is a perspective of a faucet mounting embodying my new design.

Fig. 2 is a side elevation thereof.

Fig. 3 is an end elevation thereof.

I claim:

The ornamental design for a faucet mounting substantially as shown.

ROBERT S. GROGAN.
